UNITED STATES PATENT OFFICE

BARNEY BILLET, OF NEW YORK, N. Y.

SKULL FORM

Application filed September 30, 1929. Serial No. 396,374.

This invention relates to skull forms used in producing the animal head portions of boas, scarfs and other fur pieces. Skull forms of this type generally include a hollow head portion having a more or less elongated snout portion, together with a clamping member which forms the lower jaw of the animal head and is used to hold the fur piece in position on the wearer, the skull form being covered with suitable fur to simulate the head of an animal. The clamping member may consist of upper and lower parts, the upper part being supported within the snout portion, as for instance upon a jaw plate 15 which forms the base of the snout portion.

The primary object of the present invention is to efficiently support the jaw clamp upon the jaw plate.

A further object is to enable the jaw plate 20 to perform a double function of strengthening the upper jaw of the animal head and supporting the clamping member in interlocking relation.

A still further object is to simplify and improve the construction of the jaw plate and clamping member and render the same quickly and easily attachable to the skull form.

Another object is to provide the jaw plate 30 with integral fastening devices for use in attaching the jaw plate to the skull.

Still another object is to enable the eyes to be secured in place so that they can not become loosened or pull out, and so that the 35 securing means for the eyes will not damage the material of the skull or the fur.

Other objects and advantages of the invention will be hereinafter specifically pointed out, or will become apparent, as the specification proceeds.

With the above indicated objects in view, the invention resides in certain novel constructions and combinations and arrangements of parts, clearly described in the following specification and fully illustrated in the accompanying drawings, which latter show embodiments of the invention as at present preferred.

Figure 1 is a longitudinal sectional view 50 through the skull showing the jaw plate sup-

ported within the snout portion and the jaw clamps interlocked on the jaw plate.

Figure 2 is a transverse section on the line 2—2 of Figure 1.

Figure 3 is a perspective view of the jaw 55 plate prior to its attachment to the snout portion of the skull.

Figure 4 is a perspective view of the skull taken from the rear and partly broken away 60 to show the parts below.

The skull form 10 in this instance includes a hollow head portion 11 and a snout portion 12. The snout portion 12 is adapted to form the upper jaw of the animal head and to support a jaw clamp 13 which constitutes the 65 lower jaw. To support this clamp 13 the snout portion 12 preferably includes a jaw plate 16. This jaw plate may be formed integral with, or of the same material as, the skull form 10; or it may be made of any suf- 70 ficiently firm material.

In this instance however, the jaw plate is shown as a stamped metal member 16. The snout portion 12 has a recessed portion 14, and a groove 15 extending upward from said recessed portion. The jaw plate 16 is adapted to seat in the recessed portion 14; and this jaw plate 16 in the present instance is shaped to fit the snout recess 14. The plate 16 includes a central longitudinal depression or groove 17 adapted to be aligned with the groove 15 of the snout, a plurality of integral, upturned tongue portions 18 and 19 at the right and left sides of the plate, respectively, an integral upturned rearward portion 20, shaped to fit the interior of the skull at the base of the snout, and a rearwardly extending projection 21. The forward end of the plate 16 is provided with a depression 23 at the end of its groove 17. 85

To attach the jaw plate to the snout 12, the tongues 18 and 19 are pressed into grooves or apertures 24 and 25 at the respective sides of the snout, until the plate 16 seats in the recessed portion 14, and the tongues 18 and 19 are then bent outward and downward against the outer sides, thus holding the plate firmly in place with the depression 17 aligned with the groove 15, and with the rearward portion 20 of the plate 16 95 100

abutting against the forward skull wall 26 at the base of the snout. Therefore, while a portion of the material of the snout 12 extends below the plate 16, as shown in Fig. 2, 5 said portion, particularly when the material is molded to the plate, may embrace the lower surface of the plate, as far inwardly as the central portion of rib 17, which latter may remain exposed through the said material 12.

10 The skull is then covered with suitable fur 27, the fur being stretched entirely over the snout, and covering the lower part of the jaw plate.

15 The eyes 28 are then inserted in the skull wall 26, and the wire prongs 29 of the eyes are wound around the rearward projection 21 of the plate 16, thus securely holding the eyes in place so that they cannot become 20 loosened, and so that no damage to the skull wall can result.

25 The upwardly extending portion 20 has a central opening 30 to afford access to the longitudinally forwardly extending opening produced by the groove 15 and depression 17.

30 The jaw clamp 13 includes upper and lower members 31 and 32 respectively pivoted to each other at 33 and constantly urged to closing position by a suitable spring 34. The leading and slightly tapered end of the upper member 31 of the jaw clamps is adapted to be initially inserted in the rear and slightly expanded end of the forwardly extending opening formed by the groove 15 and 35 depression 17; this member 31 having a longitudinally extending rib 35 at its under side adapted to traverse the depression 17 of the jaw plate and hold the jaw clamp against transverse movement. As the recess 40 15 is expanded at its rear end (see Fig. 1), and as the member 31 is slightly tapered at its forward end, corresponding generally with the plate 16 and its groove 17, as shown in Fig. 3, the said forward end conveniently 45 enters the recess, initially, and then moves downwardly, during the subsequent inserting operation, to the position just below the recess, or, in fact, the bottom part of the recess, shown in Fig. 2. To hold the jaw 50 clamp in place within the snout against unintentional removal, the member 31 has a downturned portion 36 adapted to lodge in the forward depression 23 in interlocking relation. The jaw clamp is then securely 55 held in place within the snout, the under side of the snout engaging the upper jaw clamp member at the sides of the latter throughout its length. The lower member 32 of the jaw clamp is adapted to constitute the lower jaw 60 of the animal, for use in holding the piece of fur in place on the wearer in a conventional manner. This lower member 32 may be covered with fur, velvet or fabric material, or any other suitable material.

65 The jaw plate 16 may be formed as a flat

plate if desired, without the depressions 23 and 17, or portions 20 or 21; and other fastening means may be used in place of the tongues 18 and 19.

While I have shown the skull form proper 70 constructed of relatively thin rubber, it may be constructed of fibrous material, impregnated burlap, buckramate or the like.

The hereinbefore described construction admits of considerable modifications without departing from the invention; therefore, I do not wish to be limited to the precise arrangements shown and described, which are, as aforesaid, by way of illustration merely. In other words, the scope of protection contemplated is to be taken solely 80 from the appended claims, interpreted as broadly as is consistent with the prior art.

What I claim as new:

1. A skull form for animal heads of fur 85 pieces, comprising a head portion including a snout and forming the upper jaw of the head, a jaw plate comprising a plurality of tongues secured in said snout, and a jaw clamp including upper and lower pivoted members and having means constantly urging 90 said jaw clamp members in closing direction, said upper jaw clamp member mounted above said jaw plate, and said lower jaw clamp member constituting the lower 95 jaw of the animal head.

2. A skull form for animal heads for fur pieces comprising a hollow head portion including a snout and forming the upper jaw of the head, a jaw plate comprising a member supported beneath said snout, eyes having prongs penetrating the skull wall, an integral projection on said jaw plate intermediate said eyes, said prongs secured on said integral projection, and a jaw clamp including upper and lower pivoted members and having means constantly urging said members in closing direction, the upper member being supported within said snout and the lower member constituting the lower jaw of 110 the animal head.

3. A skull form for animal heads of fur pieces, comprising a hollow head portion including a snout, said snout forming the upper jaw of the head, a jaw plate comprising 115 a sheet metal member beneath said snout, said jaw plate including an integral upwardly extending member to support the top of the top of the skull form at the rearward wall of said snout, a jaw clamp including upper and lower pivoted members and having means constantly urging said jaw clamp members in closing direction, said upwardly extending jaw plate member having an opening therein, and said upper jaw clamp member extending through said opening and being supported on said jaw plate, said lower jaw clamp member constituting the lower 120 jaw of the animal head.

4. A skull form for animal heads of fur 130

pieces, comprising a head portion including a snout and forming the upper jaw of the head, said snout having a recessed portion at its under side and a groove extending upward from said recessed portion, a jaw plate mounted in said recessed portion, said jaw plate comprising a sheet metal member, a jaw clamp including upper and lower pivoted members and having means constantly urging said jaw clamp members in closing direction, said upper jaw clamp member including a portion insertable in the groove of said snout for embracing said jaw plate in said recessed portion, said lower jaw clamp member constituting the lower jaw of the animal head.

5. A skull form for animal heads of fur pieces, comprising a head portion including a snout and forming the upper jaw of the head, a jaw plate secured to said snout, said jaw plate comprising a sheet metal member having a plurality of integral tongues, said snout having grooves to receive said tongues and said tongues being bent against portions 20 of said snout to secure said jaw plate in place within the skull form, and a jaw clamp including upper and lower pivoted members and having means constantly urging said jaw clamp members in closing direction, said upper jaw clamp member being supported on said jaw plate, said jaw plate having a forward depression and said upper jaw clamp member having a downturned portion engaging said forward depression and holding 25 the jaw clamp members in place in interlocking relation, said lower jaw clamp member constituting the lower jaw of the animal head.

6. A skull form for animal heads of fur pieces, comprising a hollow head portion including a snout and forming the upper jaw of the head, said snout having at its under side a recess and a groove extending upward from said recess, a jaw plate seated in said recess, said jaw plate comprising a sheet metal member having a longitudinally extending central depression to align with the groove, a plurality of integral tongues on said jaw plate, said snout having apertures to receive said tongues and said tongues being bent outward and downward against the sides of said snout to secure said jaw plate in place within the skull form, eyes having prongs positioned in the skull wall, an integral projection on said jaw plate intermediate said eyes, said prongs secured on said integral projection, and a jaw clamp including upper and lower pivoted members and having means constantly urging said jaw clamp members in closing direction, said upper jaw clamp member having a longitudinally extending rib to traverse the depression of the jaw plate, and said lower jaw clamp member constituting the lower jaw of the animal head.

7. A skull form for animal heads of fur

pieces, comprising a hollow head portion including a snout and forming the upper jaw of the head, said snout having a recessed portion at its under side and a groove extending upward from said recessed portion, a jaw plate seated in said recessed portion, said jaw plate comprising a sheet metal member having a longitudinally extending central depression to align with the groove of said recessed portion, a plurality of integral tongues on said jaw plate, said snout having grooves to receive said tongues, said tongues being bent against the sides of said snout to secure said jaw plate in place within the skull form, said jaw plate including an upwardly extending member to support the top of the skull form at the rearward wall of said snout, and a jaw clamp including upper and lower pivoted members, and having means constantly urging said jaw clamp members in closing direction, said upwardly extending jaw plate member having an opening aligned with the groove of the snout and with the depression of the jaw plate, said upper jaw clamp member having a longitudinally extending rib to traverse the depression of the jaw plate, and said lower jaw clamp member constituting the lower jaw of the animal.

8. A skull form for animal heads of fur pieces, comprising a hollow head portion including a snout and forming the upper jaw of the head, said snout having a recessed portion at its under side, a jaw plate seated in said recessed portion, said jaw plate comprising a sheet metal member, means to secure said jaw plate to said snout, eyes having prongs projecting from the skull wall, an integral projection on said jaw plate intermediate said eyes, said prongs secured on said integral projection, and a jaw clamp including upper and lower pivoted members and having means constantly urging said jaw clamp members in closing direction, said jaw plate having a forward depression and said upper jaw clamp member having a downturned portion positioned in said forward depression and holding the jaw clamps in place in interlocking relation with said jaw plate, said lower jaw clamp member constituting the lower jaw of the animal.

9. A skull form for animal heads of fur pieces, comprising a hollow head portion including a snout and forming the upper jaw of the head, a jaw plate secured beneath said snout, said jaw plate including an upwardly extending member to support the top of the skull form at the rearward wall of said snout, and a jaw clamp including upper and lower pivoted members and having means constantly urging said jaw clamp members in closing direction, said upwardly extending jaw plate member having an opening aligned with the snout, said upper jaw clamp member extending through said opening between said jaw plate and snout, said jaw plate having a

forward depression and said upper jaw clamp member having a downturned portion disposed in said forward depression and holding the jaw clamp members in place in interlocking relation, said lower jaw clamp member constituting the lower jaw of the animal head.

10. A skull form for animal heads of fur pieces, comprising a hollow head portion including a snout and forming the upper jaw of the head, said snout having at its under side a recess and a groove extending upward from said recess, a jaw plate seated in said recess, said jaw plate comprising a sheet metal member having a longitudinally extending central depression aligned with the groove and recess, a plurality of integral tongues on said jaw plate, said snout having apertures to receive said tongues and said tongues being bent against the sides of said snout to secure said jaw plate in place within the skull form, eyes having prongs penetrating the skull wall, an integral projection on said jaw plate intermediate said eyes, said prongs being secured on said integral projection, and a jaw clamp including upper and lower pivoted members and having means constantly urging said jaw clamp members in closing direction, said upper jaw clamp member having a longitudinally extending rib to traverse the depression of the jaw plate, said jaw plate having a forward depression and said upper jaw clamp member having a downturned portion disposed in said forward depression and holding the jaw clamp members in interlocking relation, said lower jaw clamp member constituting the lower jaw of the animal head.

11. A skull form for animal heads of fur pieces, comprising a hollow head portion including a snout and forming the upper jaw of the head, said snout having at its under side a recess and a groove extending upward from said recessed portion, a jaw plate seated in said recess, said jaw plate comprising a sheet metal member having a longitudinally extending central depression aligned with the groove in said recess, a plurality of integral tongues on said jaw plate, said snout having apertures to receive said tongues and said tongues being bent outward and downward against the sides of said snout to secure said jaw plate in place within the skull form, said jaw plate including an upwardly extending member to support the top of the skull form at the rearward wall of said snout, eyes having prongs penetrating the skull wall, an integral projection on said jaw plate intermediate said eyes, said prongs secured on said integral projection, and a jaw clamp including upper and lower pivoted members and having means constantly urging said jaw clamp members in closing direction, said upwardly extending jaw plate member having an opening aligned with the groove of the snout and depression of the jaw plate, said upper jaw clamp member having a lon-

gitudinally extending rib to traverse the depression of the jaw plate, said jaw plate having a forward depression and said jaw clamp member having a downturned portion positioned in said forward depression and holding the jaw clamp in place in interlocking relation, said lower jaw clamp member constituting the lower jaw of the animal head.

12. A skull form for animal heads for fur pieces, comprising an upper jaw plate having a longitudinal central depression therein, a projection at the rear end of said depression, a snout laterally and forwardly embracing said jaw plate and extending partly below the lower surface of said jaw plate, said snout having a recess therein above the jaw plate, a rear skull shell portion integral with said snout, an upwardly turned terminal carried by said jaw plate and supporting said shell, said terminal embracing the rear end of said snout and having therein an aperture, which latter communicates with said recess, eyes having retaining prongs projecting through the rear end of said snout and through said aperture, the terminals of said prongs being anchored on said projection, a jaw clamp including upper and lower pivoted members and having means constantly urging said members in closing direction, said upper jaw member, being insertable in said aperture, positioned in said recess, said lower member positioned below said plate and constituting the lower jaw of the animal head, and a rib integral with said upper jaw and positioned in the depression of said plate to maintain said jaw clamp in longitudinal alignment with said plate.

13. A skull form for animal heads for fur pieces, comprising an upper jaw plate having a longitudinal central depression therein, a snout laterally and forwardly embracing said jaw plate and extending partly below the lower surface of said jaw plate, said snout having a recess therein above the jaw plate, a rear skull shell portion integral with said snout, eyes having retaining prongs projecting through the rear end of said snout and secured inside the skull shell portion, a jaw clamp including upper and lower pivoted members and having means constantly urging said members in closing direction, said upper jaw member being positioned in said recess, said lower member positioned below said plate and constituting the lower jaw of the animal head, and a rib integral with said upper jaw and positioned in the depression of said plate to maintain said jaw clamp in longitudinal alignment with said plate.

In testimony whereof I hereby affix my signature.

BARNEY BILLET.
